UNITED STATES PATENT OFFICE

2,598,927

DENTAL IMPRESSION TRAY

William A. May, Philadelphia, Pa.

Application May 18, 1950, Serial No. 162,670

1 Claim. (Cl. 32—17)

1

The present invention relates to dentists' impression trays of the character employed in crown and bridge work for making impressions of dental surfaces.

A purpose of the invention is to avoid the labor previously involved in reassembling the broken fragments of a crown or bridge impression molding in order to obtain the correct contour of the dental surfaces.

A further purpose is to permit breaking of the plastic molding along the line of the teeth and to secure adherence of the broken fragments to the crown or bridge tray while the broken fragments are deformed or manipulated in removing the molding and tray from the mouth of the patient.

A further purpose is to hinge the corners of the channel cross section of the crown and bridge tray by employing a fold line in cardboard and the like.

A further purpose is to make a crown or bridge tray with a backing of pliable sheet material such as cardboard folded into a channel cross section having open ends and lined with an open mesh fabric secured to the backing and providing for firm adherence of the plastic molding to the backing.

Further purposes appear in the specification and in the claim.

In the drawings I have chosen to illustrate a few only of the numerous embodiments in which my invention may appear, selecting the forms shown from the standpoint of convenience in illustration, satisfactory operation and clear demonstration of the principles involved.

Figure 1 is a perspective of the improved crown and bridge tray of the invention.

Figure 2 is a section on the line 2—2 of Figure 1.

Figure 3 is a perspective showing the crown and bridge tray with a charge of plastic molding material inserted.

Figures 4 to 7 are sections similar to Figure 2, omitting the stitching, showing the steps in making an impression.

Figure 8 is a top plan view of the completed impression of Figure 7.

Figure 9 is a section similar to Figure 2 showing a variation in the tray of the invention.

In the drawings like numerals refer to like parts throughout.

At the present time crown and bridge trays are usually made of metal. A mass of plastic material such as a plaster of the character of plaster of Paris is placed in the tray and the

2

tray and charge of plaster are inserted in the mouth of the user. After the plaster sets it is necessary for the dentist to break apart the pieces of the impression in order to remove the now-hardened plastic molding from around the teeth and gums. In the end the dentist obtains several different separate fragments of the solidified impression, and these fragments constitute in effect a jig-saw puzzle which must be solved in order to assemble the parts in the proper relation prior to using the impression for manufacturing of a denture such as a crown or a bridge.

The separated fragments of the solidified plastic material do not remain adhering to the crown and bridge tray of the prior art but separate therefrom and there is always the possibility that fragments will not only become misplaced in their relation to one another but will actually be lost or swallowed in the process of removal.

In the above discussion it must be carefully kept in mind that the procedure under discussion of obtaining a crown and bridge impression is entirely different from that of obtaining a 25 "bite" impression, in which latter case wax is ordinarily used in a bite tray of obtain an impression of the mating surfaces of a set of teeth, usually including artificial dentures. In the case of a bit tray the problem of separation of a plastic molding material and reassembly of components does not exist.

In accordance with the invention I make a crown and bridge tray of a flexible backing preferably cardboard with open ends and desirably of channel shape, desirably capable of hinging at the corners of the channel, and lined with an open mesh fabric adhering to the backing. By this procedure the flexible backing can be used to manipulate the plastic material including the pieces thereof, while the pieces of plastic are held in their proper relation to one another and to the backing by the fabric lining of the backing. In this way the tray can be manipulated as a unit to break the plastic material into fragments, to hold the fragments together in their proper relation and then to reassemble the fragments.

As shown in Figures 1 and 2, the crown and bridge tray of the invention comprises a backing 20 of any suitable sheet flexible material such as cardboard, straw board or the like having a channel of U-shaped cross section forming sides or arms 21 and 22 and a bottom 23 interconnected by longitudinally extending fold lines 24. The cardboard is flexible enough so that it can

readily be hinged at the front lines under the action of the fingers and can also readily be formed at any other portion of the sheet. The ends are open as shown. It is preferable to curve the corners 25 as illustrated.

Extending over the interior surface of the backing is a lining 26 suitably of an open mesh fabric such as cotton gauze, or netting. The lining is preferably stiffened as by sizing such as starch or sugar that will make the lining lie flat.

It is important that the lining provides sufficient space between the lining and the backing so that the plastic material forming the impression can be embedded into the mesh of the lining and into the space between the lining and the backing. This is best accomplished by sewing the lining to the backing suitably by stitch lines 21, 28, 30 and 31. Any other suitable means of attachment which leaves the mesh of the fabric open may be employed.

Figures 3 to 8 show the preferred manner of forming an impression using the new crown and bridge tray.

As shown in Figure 3 a plastic mass 32 such as plaster of Paris or any other dental impression plaster, suitably flavored and perfumed, is placed in the interior of the tray. The tray is then applied in position to bring the plastic mass 32 around and against the teeth 33 and gums 34. In making an impression of upper teeth the tray will be upright, but for lower teeth the tray will be inverted as shown in Figure 4. The operator will press the tray toward the teeth to shape the molding to the teeth and gums. Once the impression has been properly formed, as shown in Figure 4, using pressure of the fingers to cause the plastic molding material to conform to the contour of the teeth and gums, the plastic material will also be thoroughly intruded into the interstices of the open mesh fabric lining so that a good bond will be obtained between the plastic material and the lining. The plastic material 32 in Figure 4 is allowed to set and thence is broken suitably along the line of longitudinal least resistance or weakest point, which usually is along the line of centers of the teeth at 35. The pressure applied for breakage can be applied to the sides of the tray with the fingers or with a dental tool, and the broken pieces 36 and 37 of the now-solidified plastic material remain in their proper place due to their intimate bonding with the fabric lining. The backing tends to bend or fold at 38 along the line of the break, permitting rocking separation of the portion 36 and 37 for the purpose of removing the solidified plastic material from the teeth by further separation of the parts as shown in Figure 6.

After the tray and the broken pieces 36 and 37 of the plastic material are removed from the mouth, the components can be reassembled by bending back the sides 21 and 22 toward one another until the structure assumes the same relationship which it had in the mouth, as shown in Figures 7 and 8. To hold the parts in the reassembled position, a suitable adhesive can be employed, such as sealing wax at 40 or other suitable adhesive such as glue or cement.

Thus it will be seen as shown in Figures 7 and 8 that the tray, which has opened up like a book about the fold line 38 established along the break 35, closes like a book as shown in Figures 7 and 8. These figures show teeth impressions 41, an impression of the lingual surface 42 and an impression of the labial or buccal surface 43.

Thus in operation it will be understood that the tray, if initially shipped flat, will be assembled into channel shape, by the fingers folding at the fold lines, will receive a charge of plastic material as in Figure 3, and hold that plastic material while it conforms to the impression of the teeth and gums as in Figure 4, thereby forming an intimate bond with the lining of the tray, and will thereafter serve to position the components of the plastic material as they are broken apart in Figure 5, separated in Figure 6, and reassembled in Figures 7 and 8. It is therefore no longer necessary for the dentist to reassemble a jig-saw puzzle, as the broken parts of the plastic material remain in their correct relationship even though the tray must be held in inverted position and even though more than one break line must be used in removing the tray from the mouth. The folding action along the break line due to the flexibility of the cardboard and due to the hinge lines at the corners of the channels, which are particularly useful in applying lateral pressure before the plastic material sets, permit the dentist to separate the parts wider and still bring them together in the correct relationship.

In some cases it may be desirable to accentuate the fold lines at the corners of the channel and this has been done in Figure 9 by a reverse bend fold at 24' at each corner.

It will be understood of course that the cardboard, lining, thread and other materials used should be of adequate purity for insertion into the mouth, and should be properly sterilized, and the cardboard particularly should be of a high enough wet strength to stand sterilizing and use in the mouth without danger of losing its shape.

In view of my invention and disclosure, variations and modifications to meet individual whim or particular need will doubtless become evident to others skilled in the art, to obtain all or part of the benefits of my structure and process shown, and I, therefore, claim all such insofar as they fall within the reasonable spirit and scope of my claim.

Having thus described my invention what I claim as new and desire to secure by Letters Patent is:

In a dental impression tray, a cardboard channel having a base and arms extending from the sides of the base and connected to the base by hinge lines, a liner of open mesh fabric extending over the inside of the base and arms, and stitching uniting the liner to the channel, whereby after making an impression in the tray, a parting line for the impression can be broken by manipulating the arms of the tray, but the impression material is held to the channel by the fabric and stitching, and the impression once out of the mouth can be reassembled by again manipulating the arms of the tray.

WILLIAM A. MAY.
